Oscar Geier

HIS ATTORNEY.

UNITED STATES PATENT OFFICE.

FRANK SYJUD, OF DETROIT, MICHIGAN.

BEVEL-PROTRACTOR.

1,278,251.

Specification of Letters Patent. Patented Sept. 10, 1918.

Application filed December 4, 1917. Serial No. 205,300.

To all whom it may concern:

Be it known that I, FRANK SYJUD, a subject of the Emperor of Austria, resident of Detroit, county of Wayne, and State of Michigan, have invented certain new and useful Improvements in Bevel-Protractors, of which the following is a specification.

This invention relates to improvements in mechanics' tools and particularly to types 10 known as bevel protractors, used in determining and laying off angles.

The principal object of the invention is to provide a tool having opposed pivotally engaged arms which may be extended uniformly and alike from a median line, thereby greatly facilitating the operations of the 15 tool.

Another object is to provide a tool in forms which may be compactly folded when 20 not in use, and which may be cheaply constructed by ordinary shop methods.

These and other like objects are attained by the novel construction and combination of parts hereafter described and shown in 25 the accompanying drawings, forming a material part of this disclosure, and in which—

Figure 1 is a top plan view of a bevel protractor made in accordance with the invention, the arms being shown in a closed 30 position.

Fig. 2 is a similar fragmental view of the same, the arms being partially opened.

Fig. 3 is a like view showing the arms fully extended.

Fig. 4 is an enlarged rear end view of 35 the protractor.

Fig. 5 is a transverse sectional view taken on line 5—5 of Fig. 1.

Fig. 6 is a similar transverse sectional 40 view taken on line 6—6 of Fig. 1.

Fig. 7 is a partial longitudinal sectional view taken on line 7—7 of Fig. 1.

Fig. 8 is a top plan view of the central 45 bar and connecting elements.

Fig. 9 is an edge view of the same.

Fig. 10 is a fragmental plan view showing one of the arms in detail.

Fig. 11 is an edge view of the same, and

Fig. 12 is a fragmental top plan view 50 showing a modified form of construction.

In the principal embodiment of the invention, a pair of arms or leaves 14 and 15 is formed with a longitudinal marginal groove or recess 16, adapted to receive part 55 of the center bar 18, the bar having a pro-

jection 19 at one end suited to recesses in the ends of the arms 14 and 15.

The opposite end of the bar has formed with it circular plates 20 and 21, adapted to be received in appropriately formed openings 22, communicating with the grooves 16, and which are held therein by rivets 24, the same passing through perforations 25 formed in the arms 14 and 15, and rigidly engaging in similar perforations 26 formed in the circular elements 20 and 21, the rivets 24 having attached to their outer ends index fingers 30, the point of which registers with a circular row of graduations 32 impressed upon the rounded ends of the arms 14 and 15, which, taken in connection with the numerals 33, permit the angle between the arms and the center bar 18 to be visually ascertained.

The rounded ends of the arms 14 and 15 are provided with extending teeth 34 and 35, the teeth of one arm intermeshing with the teeth of the other, in such manner that when one of the arms is moved relative to the center bar 18 the other arm is caused to move correspondingly, so that the angles between the arms and center bar are uniform upon each side of the latter element.

It is further to be noted that a series of 75 graduations 38 are formed upon the outer edges of the arms allowing the tool to be used as a rule or scale.

In the modification shown in Fig. 12, the arms 14 and 15 are secured by the rivets 24 to extensions 40 formed with the center bar 18, the same having a projection 41, in which is slidably engaged a rod 42, provided with an extending operating knob 43 at its outer end, and having at its lower end an enlargement 45, to which are attached links 46 and 47, the outer ends of the links being pivotally connected with the corresponding arms 14 and 15.

In operating this form of the tool it will be obvious that both arms are opened or 100 closed relative to the center bar 18 by manipulating the knob 43.

Having thus described my invention what I claim as new and desire to secure by Letters Patent, is.—

1. A bevel protractor comprising a pair of arms having a longitudinal groove in one edge thereof, a center bar adapted to be received in the groove, a head formed with said center bar, said head being engaged in 110

one end of said arms, pivotal connections between said arms and said head whereby said arms may be opened or closed relative to said center bar, said arms having a plurality of graduations arranged in a concentric row and indexes formed with the connecting means, said indexes being rigid with said center bar.

2. A bevel protractor comprising a pair 10 of arms adapted to be arranged with the edge of one adjacent to the edge of the other and containing grooves formed in the adjacent edges, a center bar receivable within the mentioned grooves, a head 15 formed with said center bar upon which the arms are pivotally engaged, a plurality of pins rigid in the said head, indexes formed with said pins, said indexes determining the angle of the opening between said arms and

said center bar, and a plurality of teeth 20 formed concentrically upon the ends of said arms, the teeth on one arm engaging with the teeth on the other so as to cause simultaneous movement of said arms.

3. In a bevel protractor, the combination 25 with a pair of arms, segmental gears formed at one end of each of said arms, a support for each of said arms, pivotal connections between said arms and said support, a bar 30 formed with said support extending centrally between said arms, a rod movable with respect to said bar, and link connections between said rod and said arms whereby both arms are operated simultaneously by the movement of said rod.

In testimony whereof I have affixed my signature.

FRANK SYJUD.
